TOY CRANE AND SELF-UNLOADING CAR

Richard G. Smith, Amsterdam, N. Y.

Application August 21, 1941, Serial No. 407,769

20 Claims. (Cl. 214—40)

This invention relates to accessory apparatus suitable for use as part of a toy railroad system and especially adapted for operating performance intended to appeal to the imagination of boys in its ability to imitate realistically certain industrial operations commonly associated with actual railroading, as for example, the loading and unloading of freight train cars with logs or other materials of industry.

One object of the invention is to provide a miniature apparatus of this kind which can operate to pick up imitation logs or other portable toy load articles one by one, and then convey each such log or article in turn and deposit it upon the platform of an open toy freight car or upon some other designed receiving structure, and if desired, to pile such logs or articles accumulatively one upon the others.

Another object is to provide a toy vehicle, as a "flat" car, which shall be operative automatically to dump or discharge its carried load of such logs or other toy load articles whether the latter have been deposited thereon in the manner described or otherwise.

Another object is to guide the travel of such logs when discharged from such self-dumping freight car so that the discharged logs shall reach a predetermined location from which each such log may be picked up, conveyed and redeposited or reloaded by the apparatus upon the same freight car. In this manner repeated loading and unloading movements of the same log with respect to the same freight car may be accomplished by the cooperative performances of a combined loading apparatus and self unloading railway car jointly embodying the present improvements.

Another object is to provide loading apparatus capable of performing movements like a combined crane and derrick structure.

A further object is to arrange an elevated portion of such crane-like structure so that it is disposed to bridge over a toy railway track and toy car that may stand and travel upon such track.

A still further object is to dispose the runway of a crane structure at an incline above and crosswise a toy freight car standing upon a toy track, and thus to provide room for a toy train, including such car, to arrive at and depart from a position beneath the included runway for receiving logs deposited by the crane and/or unloading logs under such runway.

A further object is to construct an apparatus which shall act for the foregoing purposes without dependence upon springs or similar delicate

parts which would be liable to derangement when carelessly played with by a child.

A further object is to make use of a balance of weights of gravity motivated parts as a factor in the operating performance of the apparatus, in a manner to call for the exercise of some degree of mechanical sense or skill in manipulating the controls in order to produce interesting variations in the timing and performance of different parts of the crane and derrick mechanism, particularly for determining just when and where the crane shall discharge its toy logs or other load articles.

A further object is to construct the crane and derrick apparatus as a unitary structure which may selectively be placed at and removed from different locations along a chosen stretch of track in a toy railway system.

A further object is to equip a toy car, having a load receiving and load dumping platform, with electromagnetic means adapted through electrical control to cause the platform to dump its load and then become restored to load retaining position while the car is located at a point remote from the operator.

A further object is to operate the crane and derrick apparatus by the expedient of a simple flexible cable designed to be pulled for motivating the crane and derrick parts in one direction and adapted when released to permit gravity caused action of said parts in opposite directions.

A still further object is to provide an electrically controlled and/or electrically powered prime mover for automatically pulling upon and releasing such cable at desired times.

The foregoing and other objectives will appear in greater particular from the following description of preferred forms of the invention, in which description reference is had to the accompanying drawings wherein:

Fig. 1 is a plan view of a complete toy railway accessory apparatus embodying the present improvements.

Fig. 2 is a view taken mostly in section on the vertical plane 2—2 in Fig. 1 looking in the direction of the arrows, showing the toy freight car in endwise elevation and showing progressive positions of certain other movable parts in broken lines.

Fig. 3 is a perspective view of the crane trolley drawn on an enlarged scale.

Fig. 4 is a view taken in section on the plane 4—4 in Fig. 1 looking in the direction of the arrows.

Fig. 5 is a view taken in section on the plane

5-5 in Fig. 1 looking in the direction of the arrows.

Fig. 6 is an enlarged view of the crane trolley in side elevation positioned at its limit of upward travel on the runway of Fig. 2, parts being shown as broken away better to expose the construction.

Fig. 7 is a fragmentary view taken in section through the toy freight car on the line 2-2 in Fig. 1 looking in the same direction as in Fig. 2.

Fig. 8 is a fragmentary perspective view of corner portions of certain parts of the toy car appearing in Figs. 1, 2 and 7.

Fig. 9 is a fragmentary view of the dumping mechanism of the toy car as appearing in Fig. 2 drawn on an enlarged scale.

Fig. 10 is a view like Fig. 9 showing the parts differently positioned.

Fig. 11 is a fragmentary perspective view showing a detail of hinge construction on the derrick arm.

Fig. 12 is a view similar to a portion of Fig. 2 showing a modification of electrically driven winch operating mechanism as viewed on the section plane 12-12 in Fig. 13 looking in the direction of the arrows.

Fig. 13 is a fragmentary view looking from the left at Fig. 12.

Fig. 14 is a fragmentary view taken in section on the plane 14-14 in Fig. 12 looking in the direction of the arrows.

Fig. 15 is a view similar to a portion of Fig. 12 showing still another modification of the winch motivating mechanism.

Fig. 16 is a view looking from the left at Fig. 15.

Fig. 17 is a view taken in section on the plane 17-17 in Fig. 15 looking in the direction of the arrows.

Fig. 18 is a fragmentary perspective view showing a detail of construction of the armature of the electromagnet of Fig. 17.

Fig. 19 shows some of the parts in Fig. 2 differently positioned.

Fig. 20 shows the same parts as Fig. 19 still differently positioned.

Fig. 21 is a diagram of electrical connections associated particularly with Figs. 12 to 18, inclusive.

Fig. 22 is a fragmentary plan view of the toy car taken in section on the plane 22-22 in Fig. 1.

Fig. 23 is a fragmentary view taken in section on plane 23-23 in Fig. 2.

The toy as a whole consists of two major sections or pieces of apparatus which may cooperate mutually, or perform singly, in exercising their loading and unloading functions.

One of the two major parts of the toy comprises a crane-like apparatus which serves in part as a repository for toy articles or objects such as logs dumped off from the toy flat car 10 of a toy freight train. This crane-like loading apparatus is further operative to reload these same logs, or if preferred, to load different logs upon either the same car or a different car, one by one.

The loading apparatus includes an elevated inclined runway 12 supported at its low end by a column 20 and at its high end by standard 21 and in a manner to form a bridge over the car 10 or any other piece of toy rolling stock capable of riding on rails 11 of an electrified toy track which may include the usual form of simulated rail-supporting sleepers 9. The "third" or power rail 8 of the track may be insulated in conventional manner from sleepers 9 as also is insulated a limited length of "fourth" rail 60 referred to hereinafter. Columns 20 and standard 21 of the

crane framework upstand from a common base 18 which may be formed by a horizontal rectangular skeleton frame work of sheet metal. Upstanding laterally spaced flanges 15 on base 18 provide a guideway herein taking the form of inclined ways which terminate in stop shoulders 16 at their low ends and provide a repository for toy logs 14. Base flanges 15 are cut away in the neighborhood of standard 21 to accommodate in crosswise relation thereto the track rails 11. These track rails cross over, and may be connected fixedly to, the continuous reaches of base 18 which underlies them, by solder or welding or removable screws or other equivalent means, and may form part of a course of tracks in a toy railway system not herein shown.

Inclined runway 12 incorporates laterally spaced crane rails 26 forming ways on which rides a crane trolley 24 suspended from its four traction wheels 25. Trolley 24 comprises a frame of U-shaped cross-section whose side walls flank the runway rails 26 and give bearing to cross shafts 13 on which the trolley wheels 25 are freely rotatable. The connecting belly portion of trolley 24 extends crosswise beneath rails 26 and is apertured at 19. Carried fixedly on the side walls of trolley 24 there are two inwardly offset and laterally spaced bearing brackets 27, as best shown in Fig. 6, which jointly support a hinge pin 29 on which is pivotally mounted the derrick arm 28. This derrick arm is free to swing about hinge pin 29 and has an upper short end terminating in a stub-like portion or cam follower projection 36 and has a lower long end terminating in axially spaced bearings 30 which serve as pivotal supports for hook-like hoisting devices 31.

Hoist hooks 31 may comprise terminal portions of a stiff piece of wire elsewhere bent to form bail 32 between the spaced bearings 30 of the derrick arm. Swinging movement of bail 32 is limited in an upward direction by direct contact of bail 32 with the derrick arm proper, and is limited in the downward direction by coming to rest on grapple abutment 35 which latter may be formed by continuing the stiff sheet metal of which derrick arm 28 is composed into a shelf-like extension.

A flexible cord or cable-like element 33 for pulling on the crank bail 32 and hauling trolley 24 is tied to said crank bail and passes upward through hole 19 and aperture 22 in derrick arm 28 in a direction athwart the runway and then around trolley pulley 34. Pulley 34 is rotatably supported on trolley 24 by means of cross shaft 46 whose ends bear rotatably if desired in the side walls of the trolley.

A stiff strip of metal 37 which affords a stationary elongated cam surface extends along a good part of the length of runway 12 and directly underlies, and spans the space between, and is fixedly secured to rails 26. Plate 37 is divided by a central elongated aperture 45 running lengthwise thereof which permits the passing therethrough of operating cord 33 as trolley 24 rides up or down the runway. Cam plate 37 terminates in two stiff upwardly bowed ends 38 which cooperate with the follower projection 36 of derrick arm 28 to determine when and to what angle this derrick arm and its carried hoist hooks 31 shall swing as occasioned by trolley 24 moving along the inclined runway under control of cord 33.

After passing over trolley carried pulley 34, cable 33 extends up the runway and passes one or more times around and is attached to a reel

39 which is rotatable on shaft 41 supported at a high point on standard 21. This standard may be hollow and composed of spaced side walls flanking opposite sides of pulley 39. Mounted to rotate in unison with pulley 39 is an operating drum 40 around which there is wound a number of turns of a power cord 41 whose end is fixed to the drum. This cord extends to and is secured to the bent arm 43 of a winch crank 42 which is journaled in the side walls of standard 21 and adapted to be swung manually by an arm or handle 44 exterior to standard 21. Crank 42 and its arms 43, 44 may for simplicity be formed from a continuous length of suitably bent very stiff wire or rod.

For establishing cooperative relationship between the actions of the crane apparatus described in the foregoing and the toy freight car or flat car 10, whose features of construction and operation are particularly claimed in my United States Patent No. 2,356,280, granted August 22, 1944, this car incorporates unloading means on a chassis 67 whose supporting trucks 6 and wheels 5 may be conventional for riding along the before mentioned track rails 11. Said chassis carries fixed thereon a shorter hollow raised platform 51 having end walls 68, intermediate walls 71, and a sloping edge surface 69. Outside of and adjacent each end wall 68, car chassis 67 presents a base seat 63 on which is adapted to rest, rock and slide the rounded corner edges 72 of the turned down end flanges 48 of tiltable table 52. This tiltable, load receiving table 52 is of specialized construction and is provided for normally retaining one or more logs 14 thereupon and for upon desired occasions dumping a load of such logs off onto the inclined ways 15 of the base frame of the crane apparatus. For this purpose the tiltable table 52 is provided along one of its long edges with an upstanding fixed flange 54 rigid therewith. The opposite long edge of this tiltable table is flanked by a similar load retaining flange 64 forming part of a collapsible apron 55. Apron 55 comprises an elongated L-beam type of member and includes in addition to work retaining flange 64 and in rigid relation thereto the anchored flange 65 which underlies an edge portion of tiltable table 52 and is provided at each end with a trunnion lug 56 having a pivotal bearing of controlled looseness in hole 66 in each of the down-turned end flanges 48 of tiltable table 52. When the tiltable table 52 is collapsed into horizontal or load retaining position, the anchored flange 65 of apron 55 rests upon the top surface of raised platform 51 and thus becomes fixedly sandwiched between said surface and the overlying marginal portion of tiltable table 52. This holds the load retaining flange 64 of the apron in firmly upstanding position.

A crank-like bail 53 for tilting the table 52 has its operating extremities 49 pivotally engaged respectively with the end flanges 48 of the tiltable table 52 at crank arm's length from its fulcrum bearing notches of which there are four, two being in the end walls 68 of raised platform 51 and two being in additional walls 71 intermediate end walls 68 as best shown in Fig. 22. Crank-shaft portion 70 of bail 53 is pivotally anchored in such fulcrum bearings at 50 and derives support along its entire length by resting rotatably on the top surface of raised platform 51. Centrally of bail 53 between the intermediate fulcrum bearings 50, the stiff wire which forms this bail is looped to form a downward extending bight which straddles the stem 58 of

an electromagnet plunger thereby to be actuated by the enlarged head of such plunger stem. Solenoid 59 of this electromagnet is fixedly suspended from the car chassis 51 and has its axis disposed crosswise the car.

For electrically energizing solenoid 59 one end of its winding may be grounded to the metallic chassis 67 of the car and thereby, through the trucks 6 and traction wheels 5 of the toy freight car, maintained in constant electrical circuit with the electrified track rails 11. The other end of the solenoid winding may be connected electrically to a conductive flexible current collector or shoe 61 which may take the form of a laterally projecting flexible coil of fine helically wound wire mounted at its inner end on a depending plate 62 of insulating material carried by car chassis 67. Examples of suitable details of construction for this form of current collector shoe are disclosed and claimed in my co-pending application, Serial Number 492,433, filed June 26, 1943. Collector shoe 61 is adapted to ride into and out of wiping contact with a limited length of fourth rail 60 located under the crane runway 26 and mounted on and insulated from sleepers 9 to be electrically contacted by the collector shoe while the toy car occupies a position substantially beneath the loading crane. Suitable details of construction and arrangement for this fourth rail 60 will also be found illustrated and described in the last mentioned copending application and claimed in another copending application, Serial No. 461,947, filed October 14, 1942.

The operation of the complete toy by means 35 of the crank handle 44 in conjunction with a circuit controller (not shown) for electrically energizing and deenergizing fourth rail 60 is as follows. Assuming the parts to occupy their full line positions in Figs. 1 and 2, logs 14a may or 40 may not be present on the flat car 10 at the beginning of the operation because these logs can be dumped off from the car at any time desired as hereinafter described. We will assume that logs 14a have arrived with the car 10 when the 45 latter reaches its location shown in Figs. 1 and 4 by traveling along tracks 11, and that it is desired to add a third log by picking up one of the logs 14 on ways 15 and depositing it atop logs 14a.

50 All of this may be accomplished by merely swinging crank handle 44 with reasonable slowness away from stop stud 99 in Figs. 1 and 2 to its position indicated as 44' in Fig. 2. The corresponding downward swing of crank arm 43 pulls 55 downward on power cord 41 which is wound about drum 40 and this causes pulley 39 to rotate clockwise in Fig. 2 which thereby draws cord 33 upwards of runway 12 in Fig. 2.

The first effect of this pulling on cord 33 is to 60 swing only the hoist hooks 31 from their full line position to their broken line position indicated as 31a in Fig. 2 whereupon the lower terminals of the hoist hooks encounter and begin to pick up log 14. Continued pulling on cord 33 actually 65 lifts log 14, the weight of this log now becoming added to the resistance against the pulling of cord 33 so that this cord because of passing about pulley 34 begins to haul trolley 24 up the runway 12 which action advances pivot 29 up the runway 70 conveying derrick arm 28 from its position in Fig. 2 to its position in Fig. 19. In the latter figure it is observed that cam follower nose 36 of derrick arm 28 has been diverted from a straight path of travel because of wiping against 75 the stationary cam plate terminals 38. This

forces derrick arm 28 to swing clockwise about trolley carried pivot 29 in Fig. 19 and its carried log 14 has become firmly clamped between hoist hook 31 and grapple abutment 35 by means of the clockwise swinging of hoist hooks 31 about their pivots 30.

Further log hoisting and conveying progress is evident in Fig. 20 in which the illustrated positions of parts results from continued pulling upon cord 33. Also in Fig. 20 the two remaining logs 14 on ways 15 have been permitted to roll down the ways by gravity toward stop shoulders 16 whereat the leading log will be stopped ready to be lifted by the hoist hooks when they perform their return journey for picking up a subsequent log.

Position 31b of the hoist hook and position 28b of the derrick arm are assumed as a result of continued travel of trolley 24 up the runway 12. This brings pulley 34 into position 34b and brings pivot 29 into position 29b. At this or any neighboring point in the journey of the trolley 24, if the operator should suddenly let up or play out on cord 33 by swinging crank handle 44 reversely or counterclockwise in Fig. 2, the hoist hooks would immediately swing from position 31b to position 31c under the weight of the log as carried at 14b thus permitting the log to drop to position 14c on the ways 15. The dropped log would roll down ways 15 and join the group of logs 14. So long, however, as a taut pull is maintained upon cord 33, the space between the terminals of hoist hooks 31b and the grapple abutments 35b is maintained smaller than is the log diameter so that the log cannot fall out of the hoist hook.

Finally, as a result of continued pulling upon cord 33, trolley 24 arrives at its position shown in Fig. 6 wherein trolley wheel 25 will be stopped against the upright wall of column 21. In this position of the parts shown in full lines in Fig. 6, so long as cord 33 is held taut, the log will remain in its suspended position indicated as 14d in each of Figs. 2 and 6 and approximately directly over the freight car 10. In this position of derrick arm 28 the cam plate 37 is still operative to check counterclockwise swinging of the derrick arm about pivot 29 so that if the operator suddenly lets up on cord 33, the derrick arm will perform no appreciable dropping but the log will drop from its position 14d through its positions 14e and 14f to position 14g atop the logs 14a on flat car 10. Hoist hooks 31 swing from full line position in Fig. 6 to broken line position in Fig. 6 for releasing the log and permitting it thus to be loaded on or placed aboard the freight car. A predetermined relationship of the freight car to the trackside column 21 insures that the log will drop upon the car when trolley 24 is in its uppermost stopped position as in Fig. 6.

After thus dropping its carried log responsive to sudden let-up on cord 33, as caused by smartly swinging the operating crank 42 a small degree counterclockwise in Fig. 2, continued counterclockwise swinging of crank 42 will permit pulley 39 to rotate counterclockwise and play off cord 33. The weight of trolley 24 will cause the latter to coast down the runway 12 and take up the slack in cord 33. Toward the end of this coasting down the runway, the cam follower nose 36 of derrick arm 28 encounters the upwardly bowed cam plate terminals 38 which are now being passed by the trolley traveling in the opposite direction and the derrick arm and hoist hook will pass through successive positions 31f, 28f and 31g,

28g finally becoming restored to their full line positions 31f, 28f in Fig. 2.

With reference to the loading of the toy freight car with one or more logs, it will be understood that if the car arrived at its location to be loaded in empty condition, the above described action of the crane apparatus could be repeated for first placing two logs in positions 14a, and then a third time for placing log 14g on top of the other two logs. At each excursion of derrick arms 28 up and down the runway the hoist hooks operate to pick up, convey and deposit one log, whereupon the remaining logs on ways 15 automatically advance down the ways to be picked up in their turn one-by-one. Depending upon the size of the logs in relation to the size of the freight car, any desired number of logs or bundles of toy sticks or other such toy articles capable of being handled by the hoist hooks can be loaded upon a toy freight car as desired.

It will be understood that whereas hoist hooks 31 and toy logs 14 are herein chosen to illustrate toy material and handling apparatus embodying the invention, the principles of action of the crane trolley and the derrick arm as operated by cord 33 are broadly susceptible of being employed for lifting toy bulk materials such as sand or liquids by means of any suitable container or bucket as a clam shell or dredge type of bucket, by means of which bucket the material can be conveyed to a position over the toy car and then deposited upon the car by opening or overturning the bucket. Such bucket might swing as do hoist hooks 31 or operate in other well known ways as for instance described and claimed in U. S. Patent No. 2,326,934 to scoop up and discharge toy material as part of the apparatus of the present toy.

Figs. 12, 13 and 14, show a modification consisting of the substitution of the electrically controlled application of electric power means in place of manual means for actuating the toy. Here the handle operated crank 42 is replaced by an electric motor 76 mounted on frame bracket 76 secured to base 18 by rivets 74 and whose shaft 77 serves as prime mover. A helical gear 78 fixed on a longitudinally slid able winch shaft 79 can be shifted into and out of mesh with worm 77 and thereby serves as a power disconnect clutch, capable of establishing or disconnecting power drive to a winch shaft 79. This shaft is freely rotatable and slid able lengthwise in bearings in the spaced frame brackets 80 and 81. On the left end of shaft 79 in Fig. 14 there is shown to be fixedly carried a magnetic plunger 82 which is free to rotate and slide axially in the hollow core of solenoid 83. A coiled spring 84 is lengthwise under compression between gears 78 and bracket 80 and constantly urges shaft 79 toward the right in Figs. 13 and 14. Solenoid 83 is fixedly supported on a frame bracket 85 which is removably secured to base 18 by a screw 86 and has the left end of its core cavity plugged by the stop stud 88. Stud 88 allows a predetermined extent of movement for plunger 82 toward the left in Fig. 14 when solenoid 83 is electrically energized and draws shaft 79 toward the left against the yielding resistance of spring 84. This movement of shaft 79 throws gear 78 into mesh with worm 77 as shown in Fig. 13. A shoulder 89 at the junction of shaft 79 and plunger 82 abuts against bracket 80 and limits spring urged movement of shaft 79 and gear 78 toward the right to its position shown in Fig. 14.

Between gear 78 and bearing bracket 81 a winding spool 90 on shaft 79 is rotatable relative-

ly thereto. A friction washer 91 separates spool 90 from gear 78 and constantly urges the former toward the right in Figs. 13 and 14 and against a thrust collar 92 fixed to shaft 79 by set screw 93. Thus spool 90 is caused to be rotated yieldably by shaft 79 in either direction but slippage can always take place between this spool and shaft when the load on the spool becomes excessive. Cord 33', after passing over pulley 39, extends downward to and is attached to friction driven spool 90 in a manner to be wound up on the latter and played off therefrom when spool 90 rotates in respectively opposite directions.

The wiring diagram of Fig. 21 indicates that motor 76 and solenoid 83 may be connected electrically in shunt relationship to supply lines 94 and 95 through a common circuit making and breaking switch 96 which may be located at any convenient point remote from the toy. If desired switch 96 can be located near the usual electrical controller or controllers (not shown) which serve to make or break the circuit or circuits which feed traction rails 11 together with "third" rail 8 and/or "fourth" rail 60.

Figs. 15 to 18, inclusive, show a different form of electrically controlled application of electrical power for winding up the hoist and hauling cord 33' and playing it off as desired. In this modification the winch shaft 100 is freely rotatable and freely slidable lengthwise in spaced arms 101 and 102 of bearing bracket 103 which bracket is fixedly mounted on base 18 by screws and nuts 104. Electric motor 105 also is mounted on bracket 103 and the latter affords bearing for a worm 106 axially aligned with and rotated by motor shaft 107. A helical gear 108, similar to gear 78 is made fast to winch shaft 100 by means of its hub 109 and set screw 110. Spring 111 is coiled loosely about shaft 100 and is constantly under axial compression between bracket arm 101 and gear hub 109 thus acting constantly to urge gear 108 and shaft 100 toward the right in Figs. 16 and 17. A thrust collar 112 is made fast to winch shaft 100 by means of set screw 113. The limit of movement of collar 112 and shaft 100 toward the right is determined by the swayable electromagnetic armature bar 114 which intervenes between collar 112 and bracket arm 102. This armature bar has an elongated aperture 115 in its upper end permitting said end to have tilt permitting play relative to shaft 100. Thus shaft 100 passes freely through the armature bar and this bar is in effect somewhat loosely suspended from the shaft. The bottom end of armature bar 114 is slidably fulcrumed or loosely anchored in an aperture 116 in the base 18 so that a mean section of the length of bar 114 comes within the magnetic field of the projecting core plug 117 of a solenoid 118 mounted by means of screw 122 on stationary frame bracket 119. This bracket is secured to base 18 by screws 120 and may have a cutout 121 registering with aperture 116 to assist in providing a rugged pivotal anchorage for the lower end of armature bar 114 as best shown in Fig. 18. A stop collar 123 fixed on the extreme right end of winch shaft 100 by means of set screw 124 in Fig. 16 acts as a stop to limit the lengthwise movement of this shaft toward the left to a position wherein gear 108 is in mesh with worm 106.

Just as in Figs. 12 to 14, there is mounted on shaft 100 between gear 108 and thrust collar 112, a winding spool 90 which is slippably rotatable with shaft 100 by means of a friction washer 91 which separates spool 90 from gear 108 and constantly urges spool 90 toward the right in Figs. 75

16 and 17 and against thrust collar 112. Cord 33', after passing over pulley 39, extends downward to and is attached to friction driven spool 90 in a manner to be wound up on and played off from the latter by rotation thereof in respectively opposite directions. The same scheme of electrical connections as is indicated in Fig. 21 may be employed for the apparatus of Figs. 12 to 14, motor 105 taking the place of motor 76 and solenoid 118 taking the place of solenoid 83.

In operating the crane and derrick apparatus by electrically controlled application of the power of electric motor 76 in Figs. 12, 13, 14 and 21, a remotely located switch 96 may be closed to begin the action instead of throwing handle 44 of the crank 42 as in the manually actuated form of the apparatus. This simultaneously energizes motor 76 and the solenoid 83 resulting in worm 77 rotating at full speed and gear 78 being shifted 10 toward the left from its position in Fig. 14 to its position in Fig. 13 as solenoid 83 draws magnetic plunger 82 further into its magnetic field against the resistance of spring 84. The helical teeth on gear 78 freely slide into mesh with the 15 teeth of worm 77 even if the latter be rotating at high speed. As shaft 79 is drawn lengthwise toward the left in Fig. 14 the left extremity of plunger 82 encounters the stationary magnetic core plug 88 and rotates while remaining in contact therewith. Friction between plunger 82 and plug 88 is practically eliminated by cone-pointing the contacting end of plunger 82 as shown in Fig. 14. Gear 78 is now rotated clockwise in Fig. 12 at a reasonably slow speed whereby spool 90, 20 yieldably impelled through the friction set up by washer 91, winds upon itself the cord 33'. As in the case of cord 33 in Fig. 2, this swings the hoist hooks 31, derrick arm 28 and hauls on trolley 24 thereby picking up a log 14 and conveying it up 25 the inclined runway 12. At any point in this journey of trolley 24 up the runway, cord 33' may at will instantly be freed and permitted to play out as fast as the slack can be taken up by the coasting of trolley 24 down the runway. This 30 is accomplished by merely opening switch 96 which instantly deenergizes solenoid 83 and permits spring 84 to shift gear 78 toward the right from its position in Fig. 13 to its position in Fig. 14. Thus the power drive is broken between 35 gear 78 and worm 77, the latter immediately ceasing to rotate because motor 76 becomes deprived of current at the same time. While spool 90 becomes free to rotate counterclockwise in Fig. 12 whenever switch 96 is opened so that this spool 40 90 plays off the cord 33' as fast as trolley 24 coasts down the runway 12, it will be understood that the frictional force due to spring 91, by means of which shaft 79 impels spool 90, is sufficiently great to pull trolley 24 and its carried log up the runway 12 and hence is sufficiently great at all times to prevent trolley 24 from coasting down runway 12 unless shaft 79 is made free to turn by opening switch 96. If it is desired to hold the trolley stationary at a point up the 45 runway removed from its full line position in Fig. 2, another switch 98 may be interposed in the circuit between solenoid 83 and motor 76 as as indicated in Fig. 21 so that the motor may be stopped, if desired, without deenergizing solenoid 83. This will leave gear 78 locked stationary in mesh with the non-rotating worm 77. Thereafter at will, the mere opening of switch 96 will disengage gear 78 from worm 77 and discharge a 50 log and permit the trolley to coast down hill. 55 When in the motor impelled travel of trolley 24

up the runway 12, the trolley becomes arrested in its position over car 10 because of encountering the upright wall of standard 21, the motor can continue to run and worm 71 and gear 78 can continue to rotate, spool 90 standing still because unable to further wind up on cord 33' and slippage taking place between shaft 79 and spool 90. In this stalled condition of the trolley, the moment switch 98 is opened the motor will stop running and the trolley will be unaffected because gear 78 will remain interlocked with the non rotating worm 71. But the moment switch 96 is opened, gear 78, shaft 79 and spool 90 all in unison, become free to rotate, the hoist hooks first discharge their carried log, and then the trolley coasts down the runway. It is to be observed that no movement of the trolley down the runway is necessary to permit the hoist hooks first to swing and dump their load because the trolley carried pulley 34 is entirely free to rotate while the trolley stands still and the downward pull or combined weight of the log, hoist hooks and derrick arms may keep the trolley at a stand still until the log has been discharged from the hoist hooks.

In Figs. 15 to 18, inclusive, the closing of switch 86 of Fig. 21 will be understood to energize motor 105 and solenoid 118 simultaneously which will immediately start worm 106 rotating and cause the electromagnetic core 117 to attract the armature 114 forcing the latter to swing from its position in Fig. 17 to its position in Fig. 16. This causes gear 108 to pass into mesh with worm 106 whether or not the latter is rotating and the stop collar 123 limits the travel of gear 108 toward the left to a proper position of mesh with the worm. Upon opening switch 96, spring 111 restores the parts to their positions in Fig. 17 disengaging gear 108 from worm 106. The axial distance between collar 112 and gear 108 may be the same as between collar 92 and gear 78 in Fig. 14 so that the same spool 90 and friction washer 94 may be employed as in the form of the power mechanism disclosed in Figs. 12, 13 and 14.

The particular forms of electrical power drive and clutch control herein chosen to illustrate the invention include particular features of construction in toy power winch mechanism appearing in Figs. 12 to 18, and 21 which are disclosed and claimed in a co-pending application, Serial No. 554,288, filed September 15, 1944.

The framework of the log loading apparatus may be embellished with suitable structural shape and surface coloring to imitate the appearance of actual buildings, towers, platforms, etc., commonly seen in logging camps thereby to enhance the realism of the toy. As an example, the tower house 97 is represented atop the column 21 and concealing the pulley 39 so as to give the visionary impression that all of the power mechanism is contained within the imitative house structure 97.

Many modifications of the particular forms and arrangement of parts herein disclosed to illustrate the invention will be suggested by this disclosure to workers in the art and the appended claims are directed and intended to cover all fair equivalents and commonly known substitutes for any of the particular constructions and relationships of parts herein disclosed.

I claim:

1. Toy crane apparatus for transporting toy load objects, embodying in combination, an elevated runway, a trolley supported to ride along said runway, a derrick arm carried by said trol-

ley, a hook-like device carried by said derrick arm adapted to engage a load object, and remotely controlled actuating means including a pullable cable-like element operatively engaged with both said hook-like device and said trolley for transmitting hauling force thereto.

2. Toy crane apparatus for transporting toy load objects, embodying in combination, an elevated runway, a trolley supported to ride along said runway, a derrick arm carried by said trolley, a hook-like device carried by said derrick arm adapted to engage a load object, and remotely controlled actuating means including a manually operable cable-like element operatively engaged with both said device and said trolley in a manner to transmit hauling force to said hook-like device in an up and down direction athwart said runway and simultaneously to transmit hauling force to said trolley in a direction along said runway.

3. Toy crane apparatus for transporting toy load objects as defined in claim 1, in which the said derrick arm is pivotally connected to the said trolley, and the said hook-like device is pivotally connected to said derrick arm.

4. Toy crane apparatus for transporting toy load objects as defined in claim 1, in which the said derrick arm is pivotally connected to the said trolley, and the said hook-like device has a load retaining free end and is pivotally connected to said derrick arm, together with a grapple abutment fixed on the said derrick arm in position to be approached and receded from by said free end of said hook-like device as the latter performs swinging movement relative to said derrick arm.

5. Toy crane apparatus for transporting toy load objects as defined in claim 2, in which the said derrick arm is pivotally connected to the said trolley in such manner and the said hook-like device is pivotally connected to the said derrick arm in such manner that the said hauling force transmitted by the said cable-like element urges said derrick arm and device simultaneously in respectively opposite rotary directions of swinging movement.

6. Toy crane apparatus for transporting toy load objects as defined in claim 1, in which the said runway is sufficiently inclined to enable the weight of the said trolley to drag the said cable-like element downward along said runway when said element is released from the said hauling force.

7. Toy crane apparatus for transporting toy load objects as defined in claim 1, in which the said runway is sufficiently inclined to enable the weight of the said trolley to drag the said cable-like element downward along said runway when said element is released from the said hauling force, together with a reel constructed and arranged by rotation in one direction to wind said cable-like element thereupon for exerting said hauling force and by rotation in the opposite direction to play off said element responsive to said drag of the trolley.

8. Toy crane apparatus for transporting toy load objects as defined in claim 1, in which the said derrick arm is pivotally connected to the said trolley, and the said hook-like device is pivotally connected to said derrick arm, together with an elongated cam surface stationed in fixed relation to and extending along said runway, and a follower projection carried by said derrick arm disposed to ride along and wipe against said cam surface in a manner to determine the angle

of inclination of said derrick arm relative to said runway corresponding to different positions of said trolley along the latter.

9. Toy crane apparatus for transporting toy load objects as defined in claim 1, in which the said derrick arm has a pivotal connection to the said trolley, and the said hook-like device is pivotally connected to said derrick arm, together with an elongated cam surface stationed in fixed relation to and extending along said runway, said derrick arm having a stub end portion on the opposite side of its said pivotal connection from said hook-like device disposed to wipe against said cam surface thereby to determine the angle of inclination of said derrick arm relative to said runway corresponding to different positions of said trolley along the latter.

10. Toy crane apparatus for transporting toy load objects as defined in claim 1, in which the said derrick arm is pivotally connected to the said trolley, and the said hook-like device is pivotally connected to said derrick arm, together with an elongated cam surface stationed in fixed relation to and extending along said runway and divided by a longitudinally extending cut-out through which the said cable-like element extends and along which said element rides as said trolley travels along said runway, and a follower projection carried by said derrick arm disposed to ride in engagement with said cam surface in a manner to determine the angle of inclination of said derrick arm relative to said runway corresponding to different positions of said trolley along the latter.

11. Toy crane apparatus for transporting toy load objects, embodying in combination, an elevated runway, a trolley supported to ride along said runway, a pulley rotatably carried by said trolley, a derrick arm carried by said trolley, a hook-like device carried by said derrick arm adapted to engage a load object, and remotely controlled actuating means including a cable-like element operatively engaged with said device and passing around said pulley in a manner to transmit pulling force to said hook-like device in a direction athwart said track and simultaneously to transmit hauling force to said trolley in a direction along said track.

12. In combination with toy crane apparatus for transporting toy load objects as defined in claim 1, inclined ways below the said elevated runway directed downward toward a point beneath said runway, and stop means to arrest toy objects at said point after said objects have advanced downward along said ways.

13. Toy crank apparatus for transporting toy load objects as defined in claim 1, in which the said runway is sufficiently inclined to enable the weight of the said trolley to drag the said cable-like element downward along said runway when said element is released from the said hauling force, together with a reel adapted to wind said cable-like element thereupon and to pay the same off therefrom, an electric motor, and clutch devices constituting releasable driving connections between said motor and said reel.

14. In combination with toy crane apparatus for transporting toy load objects as defined in claim 1, inclined ways below the said elevated

runway directed downward toward a station beneath said runway, and stop means to arrest toy objects at said station after said objects have advanced downward along said ways, together with a course of toy railroad track extending cross-wise said ways, and a toy car equipped with load object dumping apparatus adapted to ride along said track to a position for discharging carried load objects onto said ways.

15. The combination with a toy wheeled vehicle inpellable to a designed location in its path of travel, of apparatus near said location for unloading from and loading upon said vehicle portable toy load articles, including a crane framework upstanding beside said vehicle to a level relatively elevated thereabove, a repository for said toy load articles located beside said vehicle at a level therebelow including a guideway inclined downward in a direction away from said vehicle, unloading means carried by said vehicle operative to discharge said articles at least one at a time from said vehicle downward onto said repository, and loading means including crane-like conveyor parts ridably supported on said frame-work operative to lift said articles at least one at a time from a low point on said repository and deposit the same upon said vehicle.

16. The combination defined in claim 15, in which the said crane framework and the said guideway are elongated from the said low point in a common direction leading to the said location along their said respective levels, and the said crane-like parts are movable in said direction relative to said location.

17. The combination defined in claim 15, in which the said crane framework is structurally united with the said guideway, together with a stop for the said toy load article incorporated in the said crane framework at the low end of said guideway.

18. The combination defined in claim 15, in which the said crane framework includes ways, and the said repository includes additional ways, both of said ways extending in a common direction leading to the said location of said vehicle, and said ways being inclined from respectively different high points near said location to respectively different relatively low points relatively remote from said location.

19. The combination defined in claim 15, together with a course of railway track extending to the said location for guiding the said vehicle thereto, and structure interconnecting said track and the said crane framework and the said repository in a manner to maintain them all in fixed relationship.

20. Toy crane apparatus for transporting toy load objects as defined in claim 1, in which the said runway is sufficiently inclined to enable the weight of the said trolley to drag the said cable-like element downward along said runway when said element is released from the said hauling force, together with a reel adapted to wind said cable-like element thereupon and to pay the same off therefrom, an electric motor, and clutch devices constituting yieldable driving connections between said motor and said reel.

RICHARD G. SMITH.
